UNITED STATES PATENT OFFICE.

ALBERT TWER, OF NASSAU-ON-THE-LAHN, GERMANY.

FURNACE FOR THE HEATING OF RIVETS OR THE LIKE.

1,404,331.

Specification of Letters Patent. Patented Jan. 24, 1922.

Application filed July 22, 1920. Serial No. 398,230.

To all whom it may concern:

Be it known that I, ALBERT TWER, a citizen of the German Republic, and residing at Nassau-on-the-Lahn, Germany, have invented certain new and useful Improvement in Furnaces for the Heating of Rivets or the like, (for which I filed application in Germany, Dec. 15, 1914, and Aug. 20, 1918,) of which the following is a specification, reference being had therein to the accompanying drawing.

This invention relates to furnaces known as hearth or flame furnaces, for the heating of rivet work and the like, in which the rivets are heated in the vertical position. It is already known in such furnaces to suspend the rivets in the roof of the furnace, which operation however involves a rivet head and is objectionable on account of the breaking through of the roof. It is also known to move the rivets through the furnace placed in an upright position on the surface of a horizontal wheel. This plan however involves a complicated construction and an undesirable alteration of the furnace itself.

To obviate the above drawbacks and, in addition, to enable the heating of rivets of various dimensions, so that rivets for different machines can be heated simultaneously in the same furnace, is the object of the present invention.

This invention is carried out by the arrangement that the rivets are placed in holders of bars or in chain form, which holders can be inserted through side slots in the furnace walls and be continuously moved through the furnace. If these holders, which are preferably formed like chains, be moved continuously through the slide slots, they may in this manner be connected immediately to various machines from which the rivets pass for the purpose of being heated in the same furnace. The utilization of the furnace heat and the protective property are in this manner very considerably increased.

The accompanying drawing shows a construction of a furnace of this kind as follows:

Fig. 1 shows a vertical section,

Fig. 2 a horizontal section,

Fig. 3 a transverse section.

Figure 4 is a side elevation with a portion of the furnace in section.

Figure 4^a is a similar view of the opposite end of the device. 55

Figure 5 is a vertical transverse section of the same.

In these figures, Fig. 1 indicates the fireplace, Fig. 2 the furnace chamber on the sole of which the holders 3, here shown as bars, are located for the reception of the rivets 4 placed upright on them. The insertion of these holders takes place through the side slots 5 which correspond to the troughs 6. 60

On the furnace described above the goods are placed in the upright position in barred or chain shaped holders, which holders are inserted through side slots in the furnace walls and continuously moved through the 70 furnace. It is obvious that the application of chain shaped holders is preferable to the insertion of single bar shaped holders, because they need less handling and service. The mechanical device for the continuous 75

passing through of chain shaped holders being demonstrated in practice, several drawbacks in regard to the uniform heating of the rivets are found, and it can very easily occur that the rivets which come out of the 80 furnace cool too quickly and, on further use, prove no longer hot enough. It becomes therefore very desirable that the continuously working apparatus should be so arranged that the rivets after leaving the 85 hearth of the furnace shall be removed from the chain shaped holders as quickly as possible and be delivered to the working place. This condition is fulfilled in a special degree by the present invention. 90

In this invention, the rivets are also passed, by means of the holders falling closely one after the other, through a slot in the wall of the furnace; but the holders are not connected one to another like a chain 95 by pivoted connections. They are separate and independent one of another and lie in a channel without an end, in which they are pushed forward periodically by means of a forwarding device. The endless guidance 100 is, therefore, not completely carried out by the holders which are placed close one after

another, but there is an inter-space at the exit end of the holders about corresponding to the width of two consecutive holders. The track of the holders through the furnace 5 hearth is preferably horizontal and has at both ends semi-circular pieces connecting for the joining of the upper and the lower track. Upon this semi-circular part of the guide track, at the exit point of the rivets where 10 consequently there is no holder in the guide, there occurs, as all the holders advance, each time the result that the last holder passing out of the furnace turns over and falls with increasing rapidity downwards, through its 15 own weight, and finally again takes position in contact with the previous holder. Through this quickened descent of the last holder, the rivets inserted in it are thrown out and fall into a receptacle (30) which 20 forwards them again to another machine, one for instance for stamping the heads. The forward motion of the holders in contact one with another is effected by a push-bar with engagement catch, which engages 25 behind a nose of the last holder with the track underneath, and thus pushes forward all the previous holders. The cold rivets to be heated are inserted by the front end in the holder, which is again rising upwards. 30 The slot, through which the operation is carried on, is in the bottom of the furnace hearth under which the entire device (preferably upon a travelling support with means for causing the forward motion) rests. 35 In these drawings 2 indicates the furnace hearth through which the hot gases pass. Transversely to the hearth there is arranged through the entire bottom a narrow slot 7 which serves for the continuous travelling 40 through of the rivets 4 to be heated. These rivets are each placed loosely, three or more at a time, in corresponding cavities of narrow holders, 8, which possess at their under end at both sides two consecutively arranged 45 guide pins 9, preferably provided with rollers by means of which they are kept in the guide track. This track is formed of two sides 11 provided with guiding grooves 10. The guiding grooves pass in two parallel 50 tracks one above the other, and are connected in front and behind with semi-circular connecting pieces, so that an endless guide is formed. In this guide the holders 8 are 55 arranged close together, leaving only a space at the front turning place where two holders are left out. Each holder is provided at its inner end with a projection 12. Behind these there engages in the front holder 13, which has just come down from above to 60 the lower track, a catch 14 which is located in a slide 16 moving in guides 15. This slide is moved in one direction by means of a lever 18 engaging behind a bolt 17, and in the opposite direction by means of a 65 weighted cord 20 passing over a roller and

engaging in a holder 19. The motion of the one-armed lever 18 is effected by a projection 21 of a continuously rotating wheel 22, and the projection 21 slides preferably upon a corresponding projection 23 on the 70 lever 18. The motion of the wheel 22, provided with worm gear, is effected by a shaft 24 which can be driven by a motor 26 with gearing placed upon a bracket 25.

The entire construction is preferably supported upon a frame 27, which is movable on rails by means of its wheels 28, so that it can be drawn underneath the furnace hearth and be brought into any desired position with regard to the furnace. The catch 14, 75 serves, after each motion of the lever 18, to push the holder 8 into one division further so that the once foremost holder containing the hottest rivets at one end of the furnace hearth is pushed out along the 80 horizontal track and falls over in the direction of the arrow 29. Through the quickened downward motion and through the centrifugal force in the circular guide, the rivets are quickly thrown out and fall 85 into a bag 30 which delivers them for further operations to the respective machines.

Having now particularly described and ascertained the nature of my said invention, 90 and in what manner the same is to be performed, I declare that what I claim is:—

1. An improved rivet heating furnace embodying a hearth or flame furnace having slots, and endless holders continuously 100 moved through the furnace in said slots and the rivets held in upright position.

2. An improved rivet heating furnace embodying a hearth or flame furnace having slots, endless holders continuously moved 105 through the furnace in said slots and the rivets held in upright position, and a guide-track composed of parallel continuous horizontal members placed one above the other and having semicircular connecting pieces 110 at both ends and through which the holders freely pass unattached.

3. In a furnace for heating rivets, a hearth or flame furnace having slots, and endless holders continuously moved through the 115 furnace in said slots and the rivets held in upright position, the said holders having side projections.

4. In a furnace for heating rivets, a hearth or flame furnace having slots, endless holders continuously moved through the 120 furnace in said slots and the rivets held in upright position, the said holders having side projections, and a guide track with grooves in which said projections are 125 guided.

5. In a furnace for heating rivets, a hearth or flame furnace having slots, endless holders continuously moved through the 130 furnace in said slots and the rivets held

in upright position, the said holders having side projections, and means to engage the foremost holder immediately after it has discharged the rivets and thus the whole 5 row is pushed forward by one division.

6. In a furnace for heating rivets, a hearth or flame furnace having slots, endless holders continuously moved through the furnace in said slots and the rivets held 10 in upright position, the said holders having side projections, means to engage the foremost holder immediately after it has discharged the rivets and thus the whole row is pushed forward by one division, a 15 carrier, and means whereby the carrier is restored to normal position.

7. In a furnace for heating rivets, a hearth or flame furnace having slots, endless holders continuously moved through 20 the furnace in said slots and the rivets held

in upright position, the said holders having side projections, a guide track with grooves in which said projections are guided, and means whereby the entire rivet guiding means and its gearing is placed upon 25 a traveling carriage which can be brought into the furnace hearth in every position.

8. The improved rivet heating furnace with continuous independent moving rivet holders and travelling frame, adapted to 30 supply the furnace with rivets continuously in any position; substantially as described and shown in the drawings.

In testimony whereof I affix my signature in the presence of two witnesses.

ALBERT TWER.
